MOVING STAIRWAY

Hans E. Hansen, New York, N. Y., assignor to
 Westinghouse Electric Corporation, East Pitts-
 burgh Pa., a corporation of Pennsylvania

Application June 1, 1948, Serial No. 30,237

29 Claims. (Cl. 198—16)

1

This invention relates to conveyors and it has particular relation to moving stairways suitable for conveying passengers.

Moving stairways are employed widely for conveying passengers between different levels such as successive floors of a building. Since these levels or floors vary in vertical spacing over a substantial range, it is desirable that moving stairways be designed for ready accommodation to different vertical spacings of the successive floors.

The problem of adjusting a moving stairway to different floor heights is complicated by the fact that the stairway includes conveyor chains for controlling the movement of a plurality of similar stairway steps. The conveyor chains can be changed in length only by multiples of a dimension corresponding to the width of a stairway step. This dimension usually is of the order of 16 inches.

A moving stairway has an upper track assembly associated with upper sprocket wheels, a lower track assembly associated with lower sprocket wheels and an intermediate straight track assembly or portion which is inclined relative to the horizontal at a predetermined angle, generally of the order of 30°. Each of the track assemblies is associated with a part of a supporting structure or truss. In prior art practice the upper track assembly has been of standard construction for all installations. Also the straight portions of the track and truss have been of standard construction for all floor heights, the only differences being in the lengths of these straight portions. However, the lower track assembly has been custom built for each installation in order to provide a spacing of the sprocket wheels and a length of the tracks suitable for the required chain length for each stairway installation. Consequently, it has been impossible to stock lower track assemblies which are available for all installations.

A further problem resides in the necessity for maintaining the stairway chains taut under all conditions of operation. In prior art practice, this has been effected by mounting the lower sprocket wheels together with the associated parts of the tracks for movement as a unit with respect to the supporting structure. Suitable means are provided for biasing these sprocket wheels and the associated portions of the tracks in a direction suitable for maintaining the chains taut. Since the prior practice required relative movement between portions of the tracks, suitable sliding connections were provided for the

2

tracks. To assure continuity of the tracks for the stairway step rollers, dovetailed sliding joints were employed for the relatively movable track portions.

5 In accordance with the invention the upper sprocket wheels of a moving stairway are constructed for adjustment relative to the lower sprocket wheels of the moving stairway for a distance capable of permitting a change in the length of an associated chain corresponding to the width of one of the stairway steps. As previously pointed out, this distance usually is sufficient to permit a change in the length of the chain of 16 inches. Preferably, the adjustment is divided between the upper and lower sprocket wheels. By provision of the adjustment, it becomes possible to prefabricate in the shop complete standard upper and lower track assemblies. The only change required to accommodate the stairway design to different floor heights resides in the length of the straight truss and track portion of the stairway.

25 The adjustment of the sprocket wheels is made substantially independent of the tracks employed for guiding the stairway steps around the axes of the sprocket wheels. This permits the adoption of a substantially continuous or endless track which has no sliding or dovetailed joints.

In constructing a moving stairway according to the invention the tracks may be installed complete except for small gaps between adjacent ends of the tracks. These small gaps may be accurately measured and fillers may be introduced therein which are secured directly to the adjacent track ends. This eliminates the former practice of constructing long portions of the tracks to order with accurate dimensions for each specific installation.

30 It is therefore an object of the invention to provide an improved construction for moving stairways.

40 It is a further object of the invention to provide a moving stairway wherein a flexible unit or chain operating around spaced wheels may have the wheels adjusted relative to each other for a distance sufficient to permit a change in the length of the flexible unit corresponding to the width of an associated stairway step.

45 It is also an object of the invention to provide a moving stairway as defined in the preceding paragraph, wherein the adjustment is divided between the sprocket wheels.

50 It is a still further object of the invention to provide a moving stairway having steps movable under the control of a flexible unit operating

about spaced wheels and wherein tracks are provided for guiding portions of the steps about the axes of the wheels, at least one of the wheels being adjustable in a direction transverse to its axis relative to the associated portion of the track which guides the steps around the axis of the last-named wheel.

It is an additional object of the invention to provide a moving stairway employing upper and lower track assemblies which are prefabricated in the shop as complete standard units.

A still further object of the invention comprises the provision of a simplified track construction wherein a filler is introduced into a small gap between adjacent ends of a moving stairway track.

Other objects of the invention will be apparent from the following description taken in conjunction with the accompanying drawings, in which:

Figure 1 is a view in side elevation with parts broken away and parts omitted, of a moving stairway which may embody the invention.

Fig. 2 is a view in perspective of the lower end of a moving stairway with parts broken away embodying the invention.

Fig. 3 is a view in sectional elevation of the lower end of the moving stairway illustrated in Fig. 2.

Fig. 4 is a detail view in side elevation of a portion of the lower end of the moving stairway illustrated in Fig. 2.

Fig. 5 is a detail view in sectional elevation taken along the line V—V of Fig. 3 showing securing mechanism for portions of the tracks employed in the stairway of Fig. 2.

Fig. 6 is a view in sectional elevation of the upper end of a moving stairway corresponding to that illustrated in Fig. 1.

Fig. 7 is a detail view in side elevation showing mechanism for securing and adjusting the bearings for the sprocket wheel illustrated in Fig. 6.

Fig. 8 is a detail view in elevation showing a filler construction suitable for the tracks of a moving stairway and

Fig. 9 is a view in elevation of a filler which may be supplied with a moving stairway.

Referring to the drawings, Fig. 1 shows a moving stairway for conveying passengers between two levels which are represented as floors 1 and 2 of a building. The moving stairway comprises an upper track assembly A, a lower track assembly B and a straight track assembly or portion C. As previously pointed out, the straight portion usually is inclined at an angle relative to the horizontal of the order of 30°. Each track assembly includes track parts and parts of a supporting structure or truss which is not illustrated in Fig. 1.

The moving stairway of Fig. 1 includes a pair of spaced wheels 11 and 13 which are mounted for rotation about parallel spaced axes. These wheels are employed for guiding an endless flexible unit 15 in a continuous path. In customary practice the wheels 11 and 13 are sprocket wheels for guiding a flexible unit 15 in the form of an endless chain in a predetermined path.

The chain 15 has secured thereto a plurality of steps S. Each of the steps has a shaft 17 which passes through the chain 15 for movement therewith. Each shaft 17 carries a roller S1 which is mounted for rotation with respect to the associated shaft and which is guided in a predetermined path by means of tracks 19 and 21. As one of the shafts 17 reaches one of the

5 sprocket wheels 11 or 13, it is received within the valley between successive sprocket teeth for movement about the axis of such sprocket wheel. Consequently, the sprocket wheels serve to transfer the steps between the tracks 19 and 21. Each step also includes a roller S2 which cooperates with additional tracks represented by the track 23 in Fig. 1 for further guiding the steps. The rollers S1 and S2 of a step are spaced 10 in the direction of travel of the associated step.

Although a single flexible unit or chain may be employed, in practice the shafts 11A and 13A which support the sprocket wheels 11 and 13 are each provided with an additional sprocket wheel. 15 The sprocket wheels on each shaft are spaced axially therealong. The additional sprocket wheels would have a chain similar to the chain 15 and this chain would be associated similarly with the steps S. Also, in common practice, each step S has a pair of similar rollers at each end which cooperate in substantially the same manner with associated tracks. However, for the purpose of the present discussion it suffices to consider the parts associated with the single 20 chain 15.

A conventional electric motor 25 is provided for rotating the shaft 11A in any suitable manner. For example, the motor 25 may be connected through reduction gearing to a sprocket 30 wheel 27 which is coupled to a sprocket wheel (not shown) secured to the shaft 11A through a chain 29. Suitable motor control circuits for moving stairways are well known in the art. It may be pointed out further that the construction 35 of the steps S and their association with chains may be in accordance with the teachings of the Dunlop Patent 2,085,076.

The vertical position of the shaft 11A is fixed by the floor 2. The vertical position of the shaft 40 13A is fixed by the floor 1. The length L of the straight portion C of the tracks and associated truss is substantially determined by the height or distance between floors 1 and 2. However, the length of the chain 15 cannot be continuously varied. If it is necessary to shorten the chain, 45 one of the steps may be omitted but the chain must then be shortened a distance corresponding to the width W of the removed step S or usually approximately 16 inches. As previously pointed out, the changes in the dimensions of the 50 chain always must be multiples of this distance. As herein employed, the step width of 16" is the dimension of each of the steps S measured substantially in the direction of travel of a step as it reaches one of the sprocket wheels.

In prior art practice the track assembly A usually has been of standard construction. The construction of the tracks and the associated truss for the portion C of the moving stairway 60 has been essentially standard except for the length of the portion. The track assembly B has been custom built for each installation. To maintain the chain 15 substantially taut, it has been the practice to mount the shaft 13A slidably 65 for movement in a direction suitable for maintaining the chain 15 taut. The shaft 13A may be biased in such direction by means of a spring 31. In conformance with prior art practice, approximately $\frac{1}{2}$ inch of movement of the shaft 13A is 70 allowed for movement in either of two directions from a normal position to permit the chain 15 to follow any irregularities present in the tracks or associated sprocket wheels.

In accordance with the invention the sprocket 75 wheels 11 and 13 are adjustable relative to each

other for a distance sufficient to accommodate a change in the length of the chain corresponding to the width of one of the steps, which distance may be approximately 16 inches. Preferably, both of the shafts 11A and 13A are adjustable relative to the associated supporting structure or truss to divide the required adjustment between the two sprocket wheels 11 and 13. A suitable construction for the lower sprocket assembly may be understood more clearly by reference to Fig. 2.

Referring to Fig. 2 it will be observed that the shaft 13A has secured thereto not only the sprocket wheel 13 but an additional sprocket wheel 13B. These wheels are spaced axially along the shaft 13A. The chain 15 is guided over a substantial portion of the periphery of the sprocket wheel 13 and a similar chain 15B is guided in the same manner over the sprocket wheel 13B.

Only one of the steps S is illustrated in Fig. 2. It will be observed that the rollers S1 and S2 of this step are positioned for movement respectively along the upper tracks 19 and 23. At its opposite end the step S similarly has two rollers S1B and S2B which are positioned for movement respectively along tracks 19B and 23B which correspond to the tracks 19 and 23. Inasmuch as the chains 15 and 15B are guided for a substantial distance by their associated sprocket wheels 13 and 13B, the tracks 19 and 19B may terminate at points adjacent the sprocket wheels 13 and 13B at which the guiding function for the chains is taken over by the sprocket wheels. During the return movement of the step S the step rollers S1, S2, S1B and S2B are guided respectively by tracks 19C, 23C, 19BC and 23BC. For example the sprocket wheel 13 transfers the roller S1 between the tracks 19 and 19C. The other rollers are similarly transferred between suitable tracks.

To assure proper transfer of the rollers S2 and S2B between their upper and lower tracks, these tracks overlap adjacent the associated sprocket wheels. It will be observed that the track 23 has an arcuate portion A23 which extends about the axis of the wheel 13 and has a portion B23 running for a substantial distance adjacent and above the track 23C. Similarly the track 23C has an arcuate portion A23C which extends about the axis of the wheel 13 and about the portion A23. In addition, the track 23C has a portion B23C extending for a substantial distance above the track 23. It will be understood that as the step S descends, the roller S2 is guided between the track portions A23 and A23C about the axis of the wheel 13 and is returned to the upper end of the moving stairway along the track 23C. The construction of the tracks associated with the sprocket wheel 13B represents an image or reflection of the tracks associated with the sprocket wheel 13 and these additional tracks co-operate with the wheel 13B to guide the associated rollers in substantially the same manner.

It may be noted further that the portions of the tracks A23, A23C, B23 and B23C and adjacent portions of the tracks 23 and 23C all are secured to a plate 33 by welding or otherwise at the factory to form a complete standard unit. This plate has an opening permitting movement of the shaft 13A with respect thereto but may have a part represented by a rail 34 secured thereto which engages the top of the shaft 13A. Alternatively, the rail 34 may have an edge disposed within a circular groove extending around the shaft 13A which slidably supports the rail. It will be observed that the rail permits movement

5 of the shaft 13A relative to the plate 33 in a substantially horizontal direction. A similar plate 33B supports corresponding portions of the tracks associated with the sprocket wheel 13B in substantially the same manner.

6 The plate or supporting element 33 together with the associated portions of the tracks secured thereto comprises a complete standard subassembly which may be constructed and stocked in any desired quantity. The same comment applies to the subassembly represented by the plate 33B and associated track, and to corresponding subassemblies for the upper track assembly A which will be described below.

The tracks associated with the plate 33 may be adjusted angularly about the axis of the sprocket wheel 13 in any suitable manner. A preferred embodiment of the invention is shown clearly in Figs. 3 and 5. The supporting structure for the stairway has jack screws 35B suitable for adjusting the position of the tracks associated with the plate 33. For simplicity all parts of the supporting structure or truss are identified by the reference character ST. Thus in Fig. 3 the supporting structure includes a jack screw 35B which may be adjusted to move the plate 33 angularly about the axis of the shaft 13A. After the plate has been properly adjusted it may be secured to the supporting structure, if desired, by means of bolts 37 as clearly shown in Fig. 5. Although the plate 33 could be left resting on the shaft 13A through the rail 34 it is believed preferable to attach it securely to the supporting structure after adjustment.

35 If parts of the supporting structure, such as a bracing member, are desired adjacent the plates, the plates may be provided with openings to permit passage of such parts. For example, the plates 33 and 33B have openings 36 and 36B through which a bracing member 36C may pass. 40 Such a bracing member would be removably bolted to the supporting structure ST by means of bolts 36D.

45 Returning to Fig. 2, it will be observed that one end of the shaft 13A is mounted for rotation in a bearing 41B. This bearing is mounted on rollers 43B for movement in a horizontal direction along a platform 45B which is secured to the supporting structure. A spring 31B is compressed between the supporting structure and a washer 41B which surrounds a stud 49B projecting from the bearing 41. Such compression may be adjustably provided by means of a nut 51B which engages a threaded end of the stud. Because of this construction the spring biases the bearing 41B in a direction tending to maintain the chain 15B taut. The opposite end of the shaft 13A similarly is mounted for rotation in a bearing 41 (Fig. 4) which is biased in the same direction by means of a stud 49 and the spring 31. The bearing is mounted on rollers 43 which move on a horizontal platform 45. After the normal position of the shaft 13A is determined one or more stops 48 may be secured to the supporting structure for limiting excessive movement of the shaft.

50 It will be recalled that the invention contemplates a substantial range of adjustment for the sprocket wheels with respect to the supporting structure. For example, the shaft 13A may be adjusted in a horizontal direction over a total distance D (see Fig. 3). If the length of chain required for each step is 16 inches the distance D may be 4 inches. Since movement of the sprocket wheel 13B affects both the upper and lower runs of the chain the adjustment of the shaft 13A for

a distance of 4 inches permits a change in length of the chain of 8 inches. If the sprocket wheels at the upper end of the moving stairway may have their axis adjusted for a similar distance of 4 inches it follows that the combined adjustments permit a change in length of the chain of 16 inches. It will be recalled that the lower sprocket wheels must have an additional range of movement of the order of $\pm \frac{1}{2}$ inch from a normal position to accommodate variations in the chain length resulting from irregularities present in the moving stairway.

Referring to Fig. 3 it will be observed that the adjustment of the sprocket wheels and the shaft 13A for the desired distance D does not affect the position of the tracks in any way. Consequently, a substantially endless fixed resultant track may be presented to the rollers S2B as they pass about the axis of the shaft 13A. The effect of adjustment of the shaft 13A relative to the associated tracks is to change the tilt of the steps as they travel about the axis of the shaft. The limits of adjustment of the shaft 13A in Fig. 3 are represented respectively in full and broken lines. Similarly the positions of the steps S as they move about the axis of the shaft 13A corresponding to the two limiting adjustments of the shaft are represented in full and broken lines. It will be observed that the change in tilt of the steps is effected without requiring any substantially increased space.

It will be understood further that after the normal position of the shaft 13A is established the ends of the tracks 19, 19B may be cut to the proper dimension. These tracks may be constructed at the factory with the maximum dimension required. After the normal position of the shaft 13A is determined, the ends of the tracks may be cut or bent as required. Similar comments apply to the short tracks 55 and 55B which are positioned respectively above the tracks 19C and 19BC adjacent the sprocket wheels 13 and 13B to assist in guiding the rollers S1 and S1B. For example, in Fig. 3 as a sprocket wheel rotates in a counterclockwise direction the rollers S1B, as they leave the sprocket wheel, are received between the tracks 19BC and 55B.

The upper track assembly A is illustrated in Fig. 6. In general the same principles of construction may be followed for both of the track assemblies A and B. The shaft 11A carries at one end the sprocket wheel 11 (Fig. 1) and at the opposite end a sprocket wheel 11B (Fig. 6). These wheels cooperate respectively with the chains 15 and 15B for guiding the steps S between the upper and lower tracks. It will be noted that the track 23B has a portion C23B which is secured to a plate 59B. This plate has a rail 61 secured thereto which rests on the shaft 11A in the manner discussed with reference to the rail 34 of Fig. 2. The plate 59B of Fig. 6 may be adjusted angularly about the axis of the shaft 11A by means of a jack screw 63 which is in threaded engagement with the supporting structure ST and which engages the lower side of the track C23B for adjusting the plate 59B angularly with respect to the shaft 11A. After the plate 59B has been adjusted it may be secured to the supporting member in the manner discussed with reference to the plates in the lower track assembly.

The lower track 23BC also has a portion C23BC secured to the plate 59B. This portion has an arcuate section D23BC which extends angularly about the shaft 11A and merges into a

straight short section of track E23BC. In a similar manner the portion of the track C23B merges into an arcuate section D23B which is substantially concentric with the section D23BC. The arcuate section D23B merges into a short section of track E23B which is parallel to but spaced from the section C23B. It will be understood that as the sprocket wheel 11B rotates in a clockwise direction, step rollers S2B (which are directly behind the rollers S2 in Fig. 6) are carried up the portion 23BC of the track adjacent the sprocket wheel 11B. The step rollers S2B are guided between the track portions E23B and C23BC until they enter the space between the arcuate sections D23B and D23BC. As the steps are carried about the periphery of the sprocket wheel 11B, the rollers S2B are guided into the spaces between the track sections C23B and E23BC. They then continue down the track 23B. It will be noted that a substantially fixed continuous resultant track is provided for the rollers S2B. A somewhat similar set of tracks which is a reflection or image of the set of tracks just described, is provided in the upper track assembly for the rollers S2. The relationship of these two sets of tracks is similar to that discussed for the lower sprocket assembly.

As the steps are carried about the upper sprocket wheel the axles of the step rollers S1 and S1B are received successively in valleys between successive teeth of the upper sprocket wheels. The tracks 19B and 19BC may terminate adjacent the upper sprocket wheel 11B. Auxiliary guide tracks 64 and 65 may be included in the upper track assembly for cooperation with the tracks 19B and 19BC respectively to guide the step rollers S1B. These auxiliary tracks also may terminate adjacent the sprocket wheels of the upper track assembly. The construction of the tracks for the step rollers S1 will be understood from the discussion of the tracks for the track rollers S1B.

It will be understood that the upper sprocket wheels together with the shaft 11A preferably are adjustable in a horizontal direction for a substantial distance D'. The bearing assembly for the shaft 11A may be essentially similar to that employed for the shaft 13A. However, it suffices to provide a biasing arrangement for the lower sprocket assembly alone and for this reason provision is made for securing the bearings of the shaft 11A in any adjusted position.

A bearing assembly suitable for the shaft 11A is illustrated in Fig. 7. As shown in this figure, a bearing 69 is provided which is slidable with respect to a platform 71 secured to the supporting structure ST. The position of the bearing with respect to the platform may be adjusted by means of a stud 73 which projects from the bearing in a horizontal direction through a portion of the supporting structure ST. Nuts 75 are positioned on the stud 73 on each side of the associated portion of the supporting structure ST. The stud together with the associated bearing may be adjusted as desired in a horizontal direction. After adjustment the bearing may be secured rigidly to the platform 71 by means of bolts 77 which pass snugly through openings in the bearings and which pass through suitable slots (not shown) in the platform 71. These slots permit adjustment of the bolts in a horizontal direction for the desired distance. It will be understood that a similar bearing assembly is provided for each end of the shaft 11A.

When the desired position of the shaft 11A is

established the adjacent ends of the tracks 19B, 19BC, 64 and 65 may be cut or bent as desired in order to guide the associated step rollers to best advantage. It will be understood that the tracks are made sufficiently long for the maximum movement of the shaft 11A to the left as viewed in Fig. 6.

The shaft 11A may be adjustable over any suitable range. Under the conditions herein assumed, the shaft 11A is made adjustable in a horizontal direction for a distance D' of 4 inches. Since this adjustment affects both the upper and lower runs of the chains the adjustment of the shaft 11A is sufficient to accommodate a change in chain length of 8 inches. Inasmuch as the lower sprocket wheel shaft has a similar adjustment, the combined adjustments are sufficient for a total change in chain length of 16 inches. The positions of the shaft 11A and of the steps S, when they occupy their limiting positions, are illustrated in Fig. 6 respectively by full and broken lines.

In computing the dimensions of a stairway constructed in accordance with the invention, it may be assumed that the shafts 11A and 13A are each located at the midpoint of the respective range of adjustment thereof. The length of the straight portion C of the track and truss assembly is determined by the distance between the floors served by the stairway. The stairway is then provided with that number of steps which provides a chain length closest to that required for the assumed initial positions of the shafts 11A and 13A. The chain length having been determined, the shafts 11A and 13A may be adjusted to the positions required for the chain length so determined.

As shown in Fig. 6 the track 23B may be attached to the track portion C23B in any suitable manner as by placing the track ends in abutment and welding or otherwise securing a plate 81 to both of the ends on the lower side of the track. The tracks 23BC and 19BC similarly may be attached to the related track portions of the upper track assembly.

In prior art practice it has been the custom to calculate carefully the required length of track in the straight portion C of the stairway. Since it is virtually impossible in practice to have the ends of the tracks of the portion C snugly abut the ends of the corresponding tracks in the track assemblies A and B the proper fitting of the adjacent ends of the tracks has required appreciable and difficult field fitting.

According to the invention the portions of the stairway are calculated to provide tracks which, when fitted together, have gaps of small dimension, say 1 inch. The portions of the stairway assembly then may be secured to each other in the field. Because of tolerances to be expected in manufacture and in installation, the resulting gaps may be more or less than the 1 inch initially allowed. However, a filler F is provided for filling each of the gaps. The construction of the filler will be understood from a consideration of Figs. 8 and 9.

Referring to Fig. 9 it will be observed that the filler is of T formation. The upper bar F1 of the filler is intended to form part of the runway of the track with which it is associated. The stem F2 of the filler is a spacer for spacing the filler F from a supporting plate 85 (Fig. 8). The stem has one or more studs F3 projecting therefrom which pass through the plate 85 and which are secured thereto by means of suitable nuts 87 and washers 89.

It will be assumed that the track ends T1 and T2 were intended to be approximately 1 inch from each other, but because of the aforesaid tolerances, the tracks following installation of the stairway of which they are a part, have a gap therebetween of $1\frac{1}{2}$ inches. The filler F has a bar length F1 sufficient to take care of the maximum gap which may be encountered in practice. When a track is completely installed except for the gap to be filled by the filler, the gap is accurately measured and the ends of the bar F1 are cut to the proper dimension (represented by dotted lines in Fig. 9) to fill the gap.

The filler F together with the track ends T1 and T2 are secured to the plate 85 in a convenient manner as by bolting the various parts to the plate. As shown in Fig. 8 the filler F is secured by the stud F3 and the nut 87. The ends T1 and T2 have welded thereto spacers 91 and 93 respectively. Each of the spacers has one or more studs 95 projecting therefrom. The plate 85 is provided with openings permitting passage therethrough of the studs 95. Nuts 97 and washers 99 are provided for the studs 95 to secure the plate 85 rigidly to the spacers 91 and 93. The parts are so constructed that the filler F completely fills the gap between the track ends and forms therewith a continuous track surface for the rollers.

The nominal gap length to be allowed between track ends for reception of the filler F may be selected from a substantial range. For example, a nominal gap of 1 inch is generally within reasonable tolerances. To take care of the expected field variations in the nominal gap, the filler F may have a length of the bar F1 of the order of 3 inches. The provision of the filler F materially simplifies the construction of the tracks and supporting structure.

It is believed that the operation and installation of a complete system now may be set forth. It will be understood that the upper track assembly A and the lower track assembly B may be constructed and stocked as standard items substantially of the design illustrated in Figs. 2, 3, 4, 5 and 7. The straight portion C of the moving stairway assembly is of standard construction except for the required length. When an order is received for a stairway for operation between two floors, one of the upper track assemblies and one of the lower track assemblies are allocated for the order. The designer then assumes that the shafts 11A and 13A are located in their associated track assemblies in their median positions of adjustment. Knowing the distance between the floors, the designer computes the length of the straight portion C of the stairway. The computations are such that gaps having a nominal dimension, such as 1 inch, are left between the tracks of the straight portion C and the associated tracks of the lower track assembly B for reception of the fillers F.

The designer next computes the length of chain required for the assumed positions of the sprocket wheels. If such a chain is not of proper length for an integral number of steps S the chain is lengthened or shortened by the smallest dimension required for an integral number of steps. For example, let it be assumed that the chain as computed has a length suitable for receiving 30 $\frac{1}{2}$ steps. The designer then adopts a shorter chain having a length suitable for exactly 30 steps or a chain 2 inches shorter than the chain called for by the initial assumptions. To adjust the stairway for the shorter chain the shaft 11A in Fig. 6 would be moved $\frac{1}{2}$ inch to

11

the right from its median position and would be secured firmly in such position. If necessary for the new position of the sprocket wheels, the ends of certain of the tracks terminating adjacent the sprocket wheels may be bent or cut as required.

The various parts are installed in the building for which they are designed and filler blocks F are provided for the gaps adjacent the lower sprocket assembly. It will be recalled the nominal gaps of 1 inch are allowed to care for manufacturing and installation tolerances. Let it be assumed that one of the gaps has a final value of $1\frac{1}{2}$ inches whereas the remaining gaps have values of $1\frac{1}{8}$ inches. Three filler blocks have their bars cut to fill accurately the gaps. They are then secured in position in the manner shown in Fig. 8.

Following installation of the various stairway parts the springs 31 and 31B are adjusted by manipulation of their associated nuts to provide the desired tension on the shaft 13A. This tension maintains the shaft approximately in a position $\frac{1}{2}$ inch to the left of the median position of the range in adjustment of the shaft 13A as viewed in Fig. 3. However, it will be understood that the springs are intended to permit a reasonable range of movement of the lower shaft 13A such as $\pm\frac{1}{2}$ inch to maintain the chains taut as they follow the irregularities in the stairway guiding structure. The range of movement allowed the lower shaft is sufficient to take up the initial wear in the chain as the chain links seat themselves on their bearings. Excessive movement of the shaft 13A in a horizontal direction may be employed for actuating a conventional safety switch (not shown) in the manner disclosed in the Dunlop Patent 2,081,989.

During installation it will be recalled that the various track supporting plates such as the plates 33, 33B, 59 and 59B may be adjusted angularly about their associated shafts by operation of the jack screws provided for this purpose. After suitable adjustment, each of the plates may be secured to the supporting structure for the moving stairway.

Although the invention has been described with reference to certain specific embodiments numerous modifications thereof are possible falling within the spirit and scope of the invention.

I claim as my invention:

1. In a moving stairway, a supporting structure, an endless flexible unit, a guide for the flexible unit comprising a wheel mounted for rotation relative to the supporting structure for guiding the flexible unit about the axis of the wheel, a stairway step having a first portion secured to the flexible unit for movement therewith, and a guide substantially fixed relative to the supporting structure for guiding a second portion of the stairway step as the first portion passes about the axis of the wheel in a path spaced from the path of the first portion, the axis of the wheel being adjustable relative to the guide in a direction substantially transverse to the axis of the wheel for a substantial distance.

2. A moving stairway as defined in claim 1 in combination with mechanism for releasably retaining the axis of the wheel in adjusted positions.

3. A moving stairway as defined in claim 1 in combination with a biaser for resiliently biasing the axis of the wheel in a direction substantially transverse to said axis.

4. In a moving stairway, a supporting structure, a pair of wheels mounted for rotation rela-

tive to the supporting structure, said wheels having substantially parallel, spaced axes, an endless flexible unit engaging the wheels for movement thereabout in a predetermined circuitous path, a stairway step engaging the flexible member for movement thereby around the circuitous path, a guide substantially fixed relative to the supporting structure for guiding a portion of the stairway step during the travel of the step about one of the spaced wheels in a path spaced from said circuitous path, and adjusting means for adjusting the position of the last-named wheel in a direction substantially transverse to the axis of the last-named wheel relative to said guide.

5. In a moving stairway, a supporting structure, a pair of wheels mounted for rotation relative to the supporting structure, said wheels having substantially parallel, spaced axes, an endless flexible unit engaging the wheels for movement thereabout in a predetermined circuitous path, a stairway step having a first portion engaging the flexible unit for movement thereby around the circuitous path, a guide substantially fixed relative to the supporting structure for guiding a portion of the stairway step displaced from said first portion during the travel of the first portion around each of the wheels, and separate adjusting mechanism for adjusting the position of each of the wheels relative to the guide in a direction substantially transverse to the axes of the wheels.

6. A moving stairway as defined in claim 5 wherein the adjusting mechanism comprises a fastener for fastening a first one of the wheels in an adjusted position, and a biaser for resiliently urging a second one of the wheels in the proper direction for maintaining the flexible unit taut.

7. In a moving stairway, a stairway step, a substantially endless fixed track for guiding a part of the stairway step in an endless path, an endless chain engaging a part of the step spaced from the first-named part for controlling the movement of the step about said fixed track, a guide for the chain comprising a sprocket wheel having a substantial peripheral portion substantially spaced from the fixed track and engaging the chain, said wheel being mounted for rotation relative to the fixed track, said track having a portion extending around the axis of the wheel, the radii of the wheel and said portion being substantially different, and adjusting mechanism for adjusting the sprocket wheel relative to the fixed track in a direction transverse to the axis of the wheel.

8. A moving stairway as defined in claim 7 wherein a shaft extends through the loop formed by the endless fixed track for supporting the wheel, said shaft and wheel having clearance relative to the fixed track to permit movement of the shaft and wheel in a direction substantially transverse to the wheel axis without disturbance to said fixed track.

9. A moving stairway as defined in claim 8 wherein the fixed track has a portion substantially concentric about a second axis, the wheel axis and the second axis being parallel and adjacent each other, said adjusting mechanism being operable for adjusting the spacing between said axes, said track and the chain engaging separate portions of the step which are spaced from each other in the direction of movement of the step.

10. In a moving stairway, a supporting structure, a wheel mounted for rotation about an axis relative to the supporting structure, an endless

flexible unit having a part engaging a substantial portion of the peripheral portion of the wheel for guiding the endless flexible member continuously about the wheel axis, a step engaging the flexible unit for movement therewith, a track having a substantially fixed position relative to the supporting structure, said track having a portion curved about the axis of the wheel for guiding a part of the step around said axis, said wheel having a circular part secured thereto concentrically about the axis, said track having a member tangentially engaging the circular part for supporting the track and permitting adjustment of the wheel relative to the track in a direction transverse to the axis.

11. A moving stairway as defined in claim 10 in combination with adjusting mechanism for adjusting the track relative to the supporting structure angularly about said axis.

12. In a moving stairway, a track having two track ends defining a gap, a filler in said gap for providing a continuous track surface, said filler having a T-section in a plane intersecting the track ends and perpendicular to the track surface, and a plate bridging the gap and secured to said filler and to each of the track ends for maintaining the filler in position.

13. In a moving stairway, a rotating element, a supporting element, a track member secured to the supporting element, said track member having a portion arcuate about an axis parallel to, and adjacent the axis of the rotating element through an angle of approximately 180°, and adjusting mechanism for adjusting the supporting element angularly about the axis of the rotating element.

14. A moving stairway as defined in claim 13 wherein the track member has ends extending tangentially from said arcuate portion for substantial distances, said ends and arcuate portion being rigidly secured to the supporting element.

15. A moving stairway as defined in claim 13, wherein the supporting element has a part slidably engaging the rotating element.

16. In a moving stairway, a supporting structure, a rotating element mounted for rotation relative to the supporting structure, a supporting element, a pair of concentric tracks arcuate for substantially 180° about an axis parallel to, and adjacent to the axis of the rotating element, said tracks being secured rigidly to the supporting element to form therewith a self-sustaining unit, mechanism for directing a stairway step about the rotating element, said step having a part positioned between said concentric tracks during said direction of the stairway step about the rotating element, said supporting element being secured rigidly to the supporting structure, and means for adjusting the position of the rotating element relative to the supporting element and the tracks.

17. In a moving stairway, a track providing a tracking surface, said track having track ends defining a gap, a T-shaped filler including a bar and a stem substantially at right angles to each other, said bar having a first dimension substantially filling the gap to provide with the track a substantially continuous tracking surface, the corresponding dimension of the stem being less than the first dimension, and means securing the stem to the track ends.

18. A moving stairway as claimed in claim 17 wherein said track ends have back surfaces substantially parallel to and spaced from the tracking surface, said securing means including a

member adjacent said back surfaces and said stem, and means securing the track ends and the stem securely to the member.

19. In a moving stairway, a plurality of independently-mounted track assemblies, one of the track assemblies comprising a supporting element, a track secured to the supporting element, said track including a portion arcuate for substantially 180° about an axis, and portions forming extensions of the ends of said arcuate portion, said extensions approaching each other at positions displaced from the arcuate portion, the supporting element having an opening through which said axis extends, whereby a shaft may be passed through the opening, and a rail secured to the supporting element and extending at least partially across the opening in a direction substantially transverse to said axis, whereby the rail may rest on a shaft passing through the opening.

20. A moving stairway having a supporting structure, a pair of endless chains, said chains being located in parallel, spaced planes, an endless series of steps located between the chains, each of said steps being pivotally secured to each of the chains for rotation about a pivoting axis relative to the chains, a separate pair of spaced chain rollers rotatably secured to each of the steps for rotation about the pivoting axis 25 of the associated step, a pair of spaced first sprocket wheels disposed for rotation relative to the supporting structure about a first sprocket wheel axis for engaging respectively said chains to reverse the direction of travel thereof, first 30 mounting means mounting the sprocket wheels for rotation about said first sprocket wheel axis, a pair of spaced second sprocket wheels disposed for rotation relative to the supporting structure about a second sprocket wheel axis for engaging 35 respectively said chains to reverse the direction of travel thereof, second mounting means mounting the second sprocket wheels for rotation about the second sprocket wheel axis, said sprocket wheel axes being parallel and being located respectively adjacent the ends of the 40 stairway, and a pair of spaced step rollers for each of the steps mounted for rotation about a step roller axis which is parallel to, and spaced from the pivoting axis of the same step, track means for guiding said step rollers in paths 45 spaced from the paths of the chains as the steps move about the sprocket wheel axes, the track means and the supporting structure having sufficient clearance to permit adjustment of the sprocket wheel axes relative to each other and 50 relative to the track means by a distance corresponding to the change in the lengths of the chains required to change the number of steps by one.

60 21. A moving stairway as claimed in claim 20 wherein each of the sprocket wheel axes is adjustable relative to the supporting structure and relative to the track means for substantially one-half of said distance.

65 22. A moving stairway having a supporting structure, a pair of endless chains, said chains being located in parallel, spaced planes, an endless series of steps located between the chains, each of said steps being pivotally secured to each 70 of the chains for rotation about a pivoting axis relative to the chain, a separate pair of spaced chain rollers rotatably secured to each of the steps for rotation about the pivoting axis of the associated step, a pair of spaced first sprocket wheels disposed for rotation relative to the sup-

porting structure about a first sprocket wheel axis for engaging respectively said chains to reverse the direction of travel thereof, first mounting means mounting the sprocket wheels for rotation about said sprocket wheel axis, a pair of spaced second sprocket wheels disposed for rotation relative to the supporting structure about a second sprocket wheel axis for engaging respectively said chains to reverse the direction of travel thereof, second mounting means 10 mounting the second sprocket wheels for rotation about said second sprocket wheel axis, said sprocket wheel axes being parallel and being located respectively adjacent the ends of the stairway, and a pair of spaced step rollers for each of the steps mounted for rotation about a step roller axis which is parallel to, and spaced from the pivoting axis of the same step, in combination with adjusting mechanism operable for adjusting the spacing of the sprocket wheel axes for a substantial distance, and track means for guiding said step rollers substantially continuously during continuous rotation of said sprocket wheels, said track means providing sufficient clearance for the sprocket wheels and the mounting means to permit said adjustment of the sprocket wheel axes without disturbing the position of the track means.

23. In a moving stairway, a track assembly comprising a supporting element, a track unit comprising a track portion arcuate for substantially 180° about an axis, said track unit having an opening through which the axis extends, whereby a shaft may be passed through the opening, and a rail secured to the track unit and extending at least partially across the opening in a direction substantially transverse to the axis, whereby the rail may rest on a shaft passing through said opening.

24. In a moving stairway, a supporting structure, an endless flexible unit, a guide for the flexible unit comprising first and second wheels mounted for rotation relative to the supporting structure respectively about first and second spaced axes for guiding the flexible unit in an endless path about the axes, a plurality of stairway steps distributed around the flexible unit, each of the stairway steps having a first portion engaging the flexible unit for movement therewith, and a guide substantially fixed relative to the supporting structure for guiding a portion of each of the steps about each of the spaced wheels in a path spaced from the path of the first portion, the axis of each of the wheels being adjustable relative to the guide in a direction substantially transverse to the axis of the associated wheel for a substantial distance.

25. A moving stairway as claimed in claim 24 wherein the combined ranges of adjustment of the wheels is sufficient to permit a change in the length of the endless flexible unit by a distance corresponding to the width of one of said stairway steps.

26. In a moving stairway, an upper stairway assembly including a first supporting structure, a first wheel, first bearing means mounting the first wheel on the supporting structure for rotation about a first axis, first guide means mounted on said supporting structure, said supporting structure and guide means having clearance permitting adjustment of the bearing means and first wheel in a direction transverse to the axis for a predetermined distance, a lower stairway assembly including a second supporting structure, a second wheel, second bearing means 75 between the floors served by the moving stair-

mounting the second wheel on the supporting structure for rotation about a second axis spaced from, and parallel to, the first axis, second guide means mounted on the supporting structure, said second supporting structure and second guide means having clearance permitting adjustment of the second bearing means and second wheel in a direction transverse to the second axis for a predetermined distance, an endless flexible unit for engaging the wheels and extending therearound in a circuitous path, a plurality of stairway step units distributed around the flexible unit and engaging the flexible unit for movement therewith about the circuitous path, said first guide means being positioned to engage and guide a portion of each of the step units spaced from the flexible unit as the engaged step unit moves about the first wheel, said second guide means being positioned to engage 20 and guide a portion of each of the step units spaced from the flexible unit as the engaged step unit moves about the second wheel, the sum of the predetermined distances being sufficient to permit a change in length of the flexible unit 25 corresponding to the width of one of the steps, and means for securing the bearing means in adjusted positions to the supporting structures.

27. A prefabricated stairway track assembly for location at one end of a moving stairway to 30 guide the steps of a moving stairway as the steps leave and approach the inclined run of the moving stairway extending between the floors served by the moving stairway, said track assembly comprising a substantially flat supporting element, and a track secured to the supporting element, said track having an arcuate part extending arcuately for an angle of substantially 180° about an axis transverse to the supporting element, a first extension extending from a first 35 end of the arcuate part substantially parallel to said supporting element, said first extension having a straight part adjacent the arcuate part and having an end part inclined relative to the straight part by an angle of substantially 30°, and a second extension extending from a second 40 end of the arcuate part, said second extension having an end part substantially parallel to said first-named end part.

28. A prefabricated stairway track assembly for location at one end of a moving stairway to 50 guide the steps of a moving stairway as the steps leave and approach the inclined run of the moving stairway extending between the floors served by the moving stairway, said track assembly comprising a substantially flat supporting element, and a track secured to the supporting element, said track having an arcuate part extending arcuately about an axis transverse to the supporting element to reverse the direction of the track, said track having extensions 55 extending from the ends of the arcuate part, said extensions including a straight part, whereby the straight part may be positioned in a horizontal plane to guide steps of a moving stairway 60 horizontally adjacent one end of a moving stairway, said extensions approaching each other adjacent their ends and terminating in substantially parallel ends which are inclined relative to the straight part.

29. A pair of prefabricated stairway track assemblies for location at one end of a moving stairway to guide the steps of a moving stairway as the steps leave and approach the inclined run of the moving stairway extending between the floors served by the moving stair-

way; each of said track assemblies comprising a substantially flat supporting element, and a track secured to the supporting element, said track having an arcuate part extending arcuately for an angle of substantially 180° about an axis transverse to the supporting element, a first extension extending from a first end of the arcuate part substantially parallel to said supporting element, said first extension having a straight part adjacent the arcuate part and having an end part inclined relative to the straight part by an angle of substantially 30°, and a second extension extending from a second end of the arcuate part, said second extension having an end part substantially parallel to said first named end part; said tracks defining similar, spaced, parallel paths and being located substantially between the supporting elements when the supporting elements are opposite each other.
